(57) **CLAIM**

The ornamental design for a tire for vehicle, as shown and described.

DESCRIPTION

FIG. 1 is a perspective view of a tire for vehicle showing my new design;

FIG. 2 is a side view of tire for vehicle shown in FIG. 1;
FIG. 3 is a front side view of the tire for vehicle shown in FIG. 1; and,
FIG. 4 is an enlarged view of a portion of the tire for vehicle shown in FIG. 1.

The broken lines in the drawings depict environment and form no part of the claim.
